CANARD AIRCRAFT

Armand Jean Thieblot, Hagerstown, Md., assignor to
Fairchild Engine and Airplane Corporation, Hagers-
town, Md., a corporation of Maryland

Filed Nov. 22, 1957, Ser. No. 48,604

Term of patent 14 years

(Cl. D71—1)

Fig. 1 is a top plan view of a canard aircraft showing my new design;

Fig. 2 is a front elevation of the canard aircraft;

Fig. 3 is a side elevation thereof;

Fig. 4 is a rear elevation of the aircraft shown in the Figs. 1-3; and

Fig. 5 is a fragmentary cross-section on the line 5—5 of Fig. 1 and illustrating the ramp in lowered position.

The dominant features of the design reside in the portions shown in full lines.

I claim:

The ornamental design for a canard aircraft, as shown and described.
